United States Patent Office

Des. 194,559

Patented Feb. 12, 1963

194,559

BOTTLE

Charles A. Rolley, Reno, Nev., and William B. Randall, Menlo Park, and Bruce Hopper, San Francisco, Calif.; said Rolley and said Randall assignors to Botany Industries, Inc., Passaic, N.J., a corporation of New Jersey

Filed Oct. 16, 1961, Ser. No. 69,866

Term of patent 14 years

(Cl. D58—6)

Fig. 1.

Fig. 2.

Fig. 3.

Fig. 4.

Fig. 5.

FIG. 1 is a side elevational view of a bottle showing our new design;

FIG. 2 is an end elevational view taken from the right of FIG. 1;

FIG. 3 is an end elevational view taken from the left of FIG. 1.

FIG. 4 is a top plan view thereof.

FIG. 5 is a bottom plan view thereof.

The dominant features of our design reside in the portions shown in full lines.

We claim:

The ornamental design for a bottle, substantially as shown and described.
